Patented Feb. 26, 1918.

3 SHEETS—SHEET 3.

UNITED STATES PATENT OFFICE.

LARS W. BODINSON, OF AURORA, ILLINOIS, ASSIGNOR TO THE AMERICAN WELL WORKS,
OF AURORA, ILLINOIS, A CORPORATION OF ILLINOIS.

CENTRIFUGAL PUMP.

1,257,793.

Specification of Letters Patent. Patented Feb. 26, 1918.

Application filed June 30, 1918. Serial No. 776,585.

To all whom it may concern:

Be it known that I, LARS W. BODINSON, a citizen of the United States, residing at Aurora, in the county of Kane, in the State 5 of Illinois, have invented certain new and useful Improvements in Centrifugal Pumps, of which the following is a specification, reference being had to the accompanying drawings.

10 This invention relates to an improved construction of centrifugal pump comprising a pumping element preferably to be placed below the surface of the water in the well and a pumping element of larger diameter 15 placed at or near the surface. The pump is particularly designed for pumping water from a deep well directly into the mains of a water supply system. By the use of a plurality of pumping elements arranged in 20 series, with the upper pumping element arranged to carry as great a proportion as possible of the complete load of the pump and with the upper pumping element readily accessible, I am enabled to reduce the strain 25 upon the lower pumping element to a minimum and to easily and quickly repair or re-adjust the upper pumping element. It is accordingly one of my principal objects to arrange the upper pumping element so as to 30 render it as readily as possible accessible for repairs or adjustment. To this end it is one of my objects to provide a new and improved two-part housing or casing for the upper pumping element comprising a sta- 35 tionary member which supports the working parts and a removable member which can be removed without dismantling the pump. It is one of the objects of this invention to provide improved means for balancing the 40 weight and the thrust of the pumping elements so as to prevent undue friction between the runners and the casings in which such runners revolve. It is another object of this invention to provide means for the 45 proper adjustment of such balancing means to make possible the ready installation of the pump. It is another object of this invention to provide an adjustable wearing-ring by which it is possible to compensate 50 for wear between the runner and the casing

part below it. It is another object of my invention to provide for the ready flushing out from the water raising elements of the sand and other sediment which accumulates therein. It is another object of this invention to provide means between the pump and the water mains for straining out the sand or other sediment so as to prevent the choking up of the mains. It is another object of this invention to improve mechanisms of this 55 type in sundry details hereinafter pointed out. The means by which I have accomplished these objects are illustrated in the drawings and are hereinafter specifically described. That which I believe to be new 60 is set forth in the claims.

In the drawings,—

Figure 1 is a central vertical section through the upper and lower portions of the pumping apparatus;

Fig. 2 is a view from the right in Fig. 1 of the connection between the pump and the main;

Fig. 3 is an enlarged detail, being a central vertical section through the balancing device;

Fig. 4 is an enlarged detail, being a central vertical section through one of the runners and the wearing-rings;

Fig. 5 is an enlarged detail, being a cross-section of the connection between the pump and the water main; and

Fig. 6 is a detail of the screen portion of the connection shown in Fig. 5.

Referring to the several figures of the drawings, 10 indicates a well pit around the mouth of a well and extending below the level of the main 11 of a water supply system. 12 indicates the casing of the well of any approved type. 13 indicates a base of 85 any approved type secured at the top of the well pit 10. 14 indicates standards rising from the base 13 supporting at its upper end a motor 15 of any suitable type adapted to be driven in any suitable manner. 16 indicates a motor shaft connected by a flexible coupling 17 of any suitable type with the upper end of the vertical pump shaft 18 which is journaled in suitable bearings in the framework. As is readily understood 90 95 100

the pump-shaft 18 is adapted to be formed of a plurality of sections joined together by means of screw-threaded couplings 19. 20 indicates a roller-bearing, the lower member 5 of which is supported on the framework 21 depending from the base 13, and the upper member 22 of which is screw-threaded upon the shaft 18, being locked in position thereon by lock-nut 23.

10 24 indicates the upper pump-casing secured to the lower end of the framework 21. As is best shown in Fig. 2, the casing 24 is made in two sections, by one of which the working parts of the upper pumping element and the working parts of the water-balancing means are supported, the other section being readily removable without disturbing the operative relation of the parts. By this expedient, access may be had whenever 20 ever desired to the upper pumping element and to the water-balancing means for adjustment or repairs. 25 indicates a closure-plate for the upper end of said casing 24, said plate 25 being provided with a packing-box 26 adapted to be provided with water for sealing purposes through a pipe 27 from any suitable source of supply. 28 indicates a check-valve of any suitable type interposed between the main 11 and the 30 upper pump member, and 29 indicates a gate-valve of any suitable type located between the check-valve 28 and the main 11.

30 indicates a well-tube connected at its upper end by means of a coupling 31 to the 35 lower end of the casing 24 and connected at its lower end by means of a coupling 32 with the lower pump-casing 33. 34 indicates a shaft-casing surrounding the shaft and protecting it from foreign matter carried by the water pumped. By the use of the casing 34, oil, water, or other suitable lubricant, can be conducted to the bearings of the shaft for lubricating and cleaning purposes, as is well understood in the art.

40 45 In the construction shown, the shaft casing 34 has a screw-threaded connection at its upper end with a bearing 31^a and is suitably connected at its lower end to the pump casing 33. As will be readily understood the 50 well-tube 30 and the shaft-casing 34 are adapted to be formed in sections joined together by any suitable coupling devices.

55 35 indicates a runner keyed or otherwise fixed upon the shaft 18 within the casing 33, said runner by its rotation with the shaft 18 being adapted to force the water in the well upward through the well-tube 30 as will be readily understood. 36 indicates a transverse port leading from the well-casing 60 and opening upon the shaft 18. As shown in Fig. 1 the lower pump-casing 33 is formed of a plurality of sections suitably joined together. As will be readily understood any suitable number of such

sections 33 provided with an appropriate 65 number of runners 35 may be used in accordance with the requirements.

37—38 indicate runners keyed or otherwise fixed upon the shaft 18 within the pump-casing 24 above flanges 39—40, respectively, extending inward from the face of said casing. 41 indicates a plate fixed in position about the shaft 18 above the runner 37.

70 In the construction shown, the plate 41 is 75 connected with the flange or ring 40 by means of webs formed integrally with said parts. The pumping unit comprising the runners 37—38 is preferably to be of the same effective capacity as the pumping unit 80 comprising one or more of the runners 35 in the bottom of the well, but is to be of such a construction and arrangement as to be capable of adding materially to the pressure of the water so as to force it upward 85 to the desired elevation. By placing the upper pumping unit at or near the surface, I am enabled to design and construct such

90 unit for the most effective operation without being unduly limited in any way in the matter of its diameter. In the designing of the lower pumping unit, on the contrary, primary consideration is to be given to the matter of raising the maximum amount of 95 water through a given well tube by means of a runner the diameter of which does not exceed the inside diameter of the well tube.

Accordingly I have constructed my upper pumping unit of a larger diameter than that of the lower pumping unit in order to obtain the greatest possible efficiency in the 100 operation of the pump as a whole. Inasmuch as that portion of the shaft 18 located above the runners 37—38 must transmit power both to such runners and to the runners of the lower pumping unit, it is preferable that the shaft be made of a larger size at its upper end portion, as is shown in

105 Fig. 1, the portion of the shaft located below the upper pumping unit being called 110 upon to apply power to the lower pumping unit only.

115 As best shown in Fig. 4 each of the runners 37—38 is provided at its lower edge with an annularly-grooved ring 42 secured thereto by means of screw-threads. 43 indicates a correspondingly-grooved ring engaging the ring 42 and held against rotation relative to said ring. In the construction

120 shown the ring 43 has a screw-threaded connection with a ring 44 which is held against rotation by means of dowel-pins 45. 46 indicates a screw-threaded ring adapted to be tightened against the ring 44 in order to

125 lock the ring 43 against rotation relative to the ring 44. 47 indicates a set-screw also adapted to be tightened against the ring 43 to prevent rotation. As will be readily

understood when the wearing-rings 42-43 become worn, the set-screw 47 and the locking-ring 46 are to be loosened whereupon the ring 43 may be screwed upward again 5 into proper engagement with the ring 42, being held in such adjusted position by means of the lock-nut 46 and the set-screw 47, as above described.

48-49 indicate drain pipes communicating at their inner ends with the runner chamber underneath the flanges 39-40, respectively, said pipes being provided at their outer ends with pet-cocks 50. 51-52 indicate pipes communicating with the runner chamber on the opposite side thereof from the pipes 48-49, said pipes 51-52 being adapted to be connected with any suitable source of water under pressure. 53 indicates stop-cocks of any suitable type interposed in the pipes 51-52. Whenever desirable, preferably when the pump is at rest, the stop-cocks 53 and the pet-cocks 50 may be opened permitting the water supplied through the pipes 51-52 to pass freely 25 across the runner chamber beneath the flanges 39-40, serving to wash out all the sand and sediment which has settled underneath said flanges from the water being pumped.

30 54 indicates a plate passing substantially across the runner chamber above the runner 38 forming a chamber 55 within the casing 24 between the plates 54 and 25. 56 indicates a pipe connecting the chamber 55 with 35 the interior of the casing 24 below the runners therein. 56^a indicates a stop-cock interposed in said pipe 56.

57 indicates pipes leading to the interior of the casing 24 and to the interior of the 40 water passage at various points therealong, the upper ends of said pipes being adapted to be connected with any suitable gages for the purpose of determining the pressure of the water at the different points of connection of said tubes with the water passage.

Referring now to Fig. 3 where the pump balancing means is shown, 58 indicates a sleeve secured upon the shaft 18 by means of a key 59 inserted in a key-way 60. Said 50 key-way 60 is of greater length than is required for the key 59 whereby the sleeve 58 may be secured upon the shaft 18 in adjusted position thereon. 61 indicates a disk mounted by means of a screw-threaded sleeve 62 upon a screw-threaded portion of the sleeve 58. The upper end of the sleeve 58 is designed to be hexagonal in shape whereby the collar 63 which has a working fit thereon is adapted to slide up and down 60 on said sleeve 58, but is held against rotation relative thereto. 64 indicates pins mounted by means of screw-threads in suitable openings in the collar 63, the lower ends of said pins being adapted to be screwed down into

engagement with suitable sockets 65 in the 65 disk 61. As will be readily understood when the pins 64 are turned out of engagement with the sockets 65 of the disk 61 the disk 61 is then free to be adjusted up and down relative to the sleeve 58 by being 70 turned relative thereto. When the sleeve 62 has been turned into the desired adjusted position the pins 64 are adapted to be again brought into engagement with the sockets 65 serving to hold the sleeve 62 and disk 61 75 against further rotation.

66 indicates a disk or ring mounted upon the plate 54 and held against rotation relative thereto by means of dowel-pins 67. Said disk is also connected by means of bolts 80 68 with a plate 69 which is spaced away from said disk 66 by a ring 70. Said disk 66 is provided with a bearing-plate 71 removably secured to its upper face in registry with a suitable bearing face on the lower 85 side of the disk 61. 72 indicates a bearing-ring suitably secured to the lower face of the disk or ring member 66, said bearing-plate 72 being, in the construction shown, of considerably smaller diameter than the 90 bearing-plate 71. Said bearing-plate 72 is also provided with an annular flange 73 which extends along the inner face of said member 66 in close contact therewith, but spaced loosely away from the exterior of the 95 sleeve 62. 74 indicates a bearing-ring mounted by means of screw-threads upon the lower end of sleeve 62.

When the pump is started into operation through the medium of the motor 15 the 100 weight of the shaft 18 and the parts connected therewith is supported by the roller-bearing 20 which relieves the friction sufficiently for starting the parts in motion. When the lower pump has forced the stream 105 of water up into the suction of the upper pump and the water is thence forced outward through the valves 28 and 29, a small portion of the water is forced between the bearing-plates 74 and 72 and upward between the sleeve 62 and the flange 73 into the chamber 75 between the disks 61 and 66. When the pressure in said chamber 75 becomes sufficient the disk 61 is forced upward, carrying with it the shaft 18 and the 110 parts mounted thereon, permitting the water to pass between the bearing-plate 71 and the edge of the disk 61. Upon the relieving of the pressure in said chamber 75 by the escape of a portion of the water the weight of the shaft 18 and its parts carries the disks 61 again downward toward the bearing-plate 71, to be again raised when the pressure in the chamber 75 becomes subsequently sufficient. The water escaping from the chamber 75 passes through suitable ports 76 in the ring 70 into the chamber 55 from which it passes through the by-pass pipe 56 to the 115 120 125

suction side of the upper pump member, as will be readily understood. In practice it is found that if the chamber 75 be properly proportioned the shaft 18 and the runners 5 mounted thereon vibrate freely up and down, relieving almost entirely the friction which would otherwise very rapidly wear the runners mounted on the shaft.

By reason of my construction, providing 10 means for the adjustment of the balancing means, no especial care need be taken in the installation of the pump as a whole with reference to the proper positioning of the balancing means, since the sleeve 62 with 15 the disk 61 can be adjusted to its proper position relative to the ring or disk 66 within a considerable latitude of adjustment.

Coming now to the means for connecting the pump with the main 11, 77 indicates a 20 section of pipe united by means of a coupling 78 with the outlet pipe of the pump beyond the valve 29. 79 indicates a T pipe section connected by means of a suitable coupling 80 to the pipe 77, the water main 25 11 being connected with the end of one of the T arms by means of a coupling 81. 82 indicates a pipe connected with the main 11 by means of a coupling 83, and extending through the pipe section 79 and substantially 30 through the pipe 77, being closed at its free end by means of a conical cap 84. 85 indicates a series of holes in the wall of the pipe 82. 86-87 indicate wire screens stretched about the pipe 82. 88 indicates a 35 downwardly-extending pipe connected with the stem of the T pipe 79 by means of a coupling 89. 90 indicates a plate secured by means of a coupling 91 to the lower end of the pipe 88. 92 indicates a stop-cock mounted on the end of a pipe 93 secured in 40 the plate 90.

As will be readily understood, when water is forced by the pump into the pipes 77-79 about the pipe 82, the water will be forced 45 through the holes 85 and through the openings of the screens 86-87 and from thence into the main 11 of the water system. The sand and other sediment which are prevented from entering the pipe 82 by the 50 screens 86-87 accumulates in the pipe 88 from which it can be washed occasionally by opening the stop-cock 92. If desired in case the water pumped contains a great deal of sand or other sediment, the stop-cock 92 can 55 be left open all the time to a slight extent so as to keep the pipe 88 substantially clear of sand.

What I claim as my invention and desire to secure by Letters Patent is:—

60 1. In a centrifugal pump, the combination of a casing, a runner adapted to be revolved therein, and pipes communicating with the interior of said casing underneath said runner one of which pipes is adapted to be

connected with any suitable source of water 65 under pressure for flushing out the sand and sediment therefrom.

2. In a centrifugal pump, the combination of a frame, a shaft extending down into the well, a runner mounted thereon for forcing 70 water out of said well, an anti-friction bearing adapted to relieve the friction between said shaft and said frame, means actuated by the pressure of the water pumped for supporting a portion of the weight of the 75 shaft so as to relieve the pressure upon said antifriction bearing, and means for adjusting said antifriction bearing and said pressure-actuated means relative to each other longitudinally of said shaft. 80

3. In a balanced centrifugal pump, the combination of a frame, a shaft extending down into the well, a runner mounted thereon for forcing water out of said well, means actuated by the pressure of the water 85 pumped for supporting said shaft against the downward pull thereon, and means for adjusting said pressure-actuated means longitudinally of said shaft.

4. In a balanced centrifugal pump, the 90 combination of a frame, a shaft extending down into the well, a runner mounted thereon for forcing water out of said well, means actuated by the pressure of the water pumped for supporting said shaft against 95 the downward pull thereon, means for adjusting said pressure-actuated means longitudinally of said shaft, and other means for locking the said pressure-actuated means against adjustment. 100

5. In a balanced centrifugal pump, the combination of a frame, a shaft extending down into the well, a runner mounted thereon for forcing water out of said well, and means actuated by the pressure of the water 105 pumped for supporting said shaft against the downward pull thereon, said pressure-actuated means comprising two inter-acting members mounted on said frame and said shaft respectively, one of 110 said members being adjustable vertically.

6. In a balanced centrifugal pump, the combination of a frame, a shaft extending down into the well, a runner mounted thereon for forcing water out of said well, and means actuated by the pressure of the water pumped for supporting said shaft against the downward pull thereon, said pressure-actuated means comprising two inter-acting members one of which is mounted on 115 said frame and the other of which is adjustably mounted on said shaft. 120

7. In a balanced centrifugal pump, the combination of a casing, a shaft rotatable therein, a runner mounted on said shaft within said casing, and means communicating with the interior of said casing actuated by the pressure of the water pumped 125

to move said shaft in the direction in which said water is being forced, said pressure-actuated means comprising two inter-acting members, one of which is mounted on said frame and the other of which is adjustably mounted on said shaft.

8. In a centrifugal pump, the combination of a casing, a shaft rotatable therein, a runner mounted on said shaft within said 10 casing, a chamber in said casing adjacent to said runner, a balancing means between said runner and said chamber, and a by-pass from said chamber to said casing on the opposite side of said runner, said balancing 15 means comprising two inter-acting members one of which is mounted on said frame and the other of which is adjustably mounted on said shaft, each of said members having a laterally-extending face adapted to oper- 20 atively contact a corresponding face of the other member.

9. In a balanced centrifugal pump, the combination of a casing, a shaft rotatable therein, a runner mounted on said shaft within said casing, and means communicating with the interior of said casing actuated by the pressure of the water pumped to move said shaft in the direction in which said water is being forced, said pressure- 25 actuated means comprising a ring-member mounted on said frame, said ring-member having two bearing-plates of different diameters, and a second ring-member adjustably mounted on said shaft, said second 30 ring-member having two bearing-plates in registry with the bearing-plates carried by said first-mentioned ring-member.

10. In a balanced centrifugal pump, the combination of a casing, a shaft rotatable 40 therein, a runner mounted on said shaft within said casing, and means communicating with the interior of said casing actuated by the pressure of the water pumped to move said shaft in the direction in which said wa- 45 ter is being forced, said pressure-actuated means comprising a ring-member adjustably mounted on said shaft and having two bearing plates of different sizes faced toward each other, and a second ring-member, 50 mounted on said frame between the bearing-plates of said first-mentioned ring-member and having bearing-plates adapted to be brought alter- 55 natively into engagement with said first-mentioned bearing-plates respectively.

11. In a balanced centrifugal pump, the combination of a casing, a shaft rotatable therein, a runner mounted on said shaft within said casing, and means communicating with the interior of said casing actuated by the pressure of the water pumped to move said shaft in the direction in which said water is being forced, said pressure-actuated means comprising a ring-member

having a screw-threaded connection with 65 said shaft and provided with two bearing-plates of different sizes faced toward each other, and a second ring-member mounted on said frame between the bearing-plates of said first-mentioned ring-member and having bearing-plates adapted to be brought alternatively into engagement with said first-mentioned bearing-plates respectively. 70

12. In a balanced centrifugal pump, the combination of a casing, a shaft rotatable 75 therein, a runner mounted on said shaft within said casing, and means communicating with the interior of said casing actuated by the pressure of the water pumped to move said shaft in the direction in which said water is being forced, said pressure-actuated means comprising a ring-member having a screw-threaded connection with said shaft and provided with two bearing- 80 plates of different sizes faced toward each other, a second ring-member mounted on said frame between the bearing-plates of said first-mentioned ring-member and having bearing-plates adapted to be brought alternatively into engagement with said first-mentioned bearing-plates respectively, and means for holding said first-mentioned ring-member against rotation. 85

13. In a balanced centrifugal pump, the combination of a casing, a shaft rotatable 90 therein, a runner mounted on said shaft within said casing, and means communicating with the interior of said casing actuated by the pressure of the water pumped to move said shaft in the direction in which said water is being forced, said pressure-actuated means comprising a sleeve fixed upon said shaft, a ring-member having a screw-threaded connection with said sleeve and provided with two bearing-plates of 100 different sizes faced toward each other, a collar movable longitudinally of said shaft upon said ring-member, but held against rotation relative thereto, means for connecting said collar with said ring-member, and a second ring-member mounted on said frame between the bearing-plates of said first-mentioned ring-member and having bearing-plates adapted to be brought alter- 110 natively into engagement with said first-mentioned bearing-plates respectively. 115

14. Means for pumping water from a well consisting of two pumps, one pump being located down in the well having its suction extending down into the water and its water discharge connected to the suction of the top pump, said pumps being driven by a vertical driving shaft connecting them, the lower pump being adapted to pump water up within pumping reach of the upper 120 pump, and the uppermost pump pumping water to the distance and height required, part of the pump cylinder casing of the 125

upper pump being capable of removal for repairs or examination, thus saving the cost of removing the whole pump.

15. The combination with a well casing, of a vertical power shaft, connecting means between two vertical centrifugal pumps one located below the surface in the well casing and the other at the surface, and means

for examining the interior of the upper pump without dismantling the pumping unit.
